UNITED STATES PATENT OFFICE.

HUBBARD HENDRICKSON, OF NEW YORK, N. Y.

BRUSH.

SPECIFICATION forming part of Letters Patent No. 230,277, dated July 20, 1880.

Application filed August 13, 1879.

To all whom it may concern:

Be it known that I, HUBBARD HENDRICKSON, of New York city, in the State of New York, have invented certain new and useful 5 Improvements relating to the Construction of Brushes, of which the following is a specification.

The invention relates to the means for attaching and confining the brush material to 10 the handle.

I will describe the brush as of bristles; but it will be understood that the stock may be hair, manila, or other brush material.

Sheet metal bent around and properly confined forms an excellent and durable confining means. It is important to confine the bristles not only laterally but endwise, so as to prevent the whole or any part of the bristles from being forced by an end pressure back- 15 ward or toward the hand of the operator. When sheet metal is employed it should be formed or bent inward, so as to protect, cover, and confine the upper ends of the bristles.

This has been before accomplished, and my 20 invention relates to an improvement upon the formation of this part, affording a construction which combines unusual strength and durability with great facility of manufacture and application.

30 In the accompanying drawings, which form a part of this specification, Figure 1 represents a side elevation; Fig. 2, an end section, and Figs. 3, 4, and 5 detail views.

Referring to the drawings, A designates the 35 handle, formed with a wedge-shaped end, A', and with a groove, a.

B represents the bristles or other brush material, and C an ordinary band, of leather, secured by nails E in the ordinary manner.

40 D D' represent my peculiar metallic fastening part or ferrule. It is cut from flat sheet metal in the form of a strip, of form to allow for the bevel of the sides, and of proper length to be tightened around the outside of the leather C, with a little lap of a width equal to the depth required (marked D) plus the inward extension, D', which covers the butts of the bristles and takes hold in the groove a in the handle.

45 The part D' is bent at about a right angle to the part D, and is slotted, as indicated at d, to facilitate the bending process, each division overlapping the edge of an adjoining part. The slitting of this part D' and having

the edge engage in the slot or groove a in the 55 handle are important features in my invention.

Near one end of the part D a short cross-slot, d', is punched or otherwise produced, as shown in Fig. 3, and at the opposite end a corresponding tongue, d'', is formed.

When the metal has been bent around in the proper position, the tongue d'' is engaged in the slot d' and secured by clinching or riveting. The metal being thus locked under a 65 moderate compression, it may be bent and held by ordinary clamps or other suitable means, (not represented,) with the inner edge of the part D locking in the groove a, and the 70 nails E hold the whole securely and tightly together.

In applying the invention to round brushes the entire part D' should be slotted uniformly. In applying it to flat brushes the slits are required only at the bent portions at the two 75 curved ends of the brush.

Various modifications may be made without departing from the principle or sacrificing the advantages of my invention, the essential features of which are the slotted piece D D' d, 80 having the locking devices d' d'' and the groove a in the handle.

I am aware of the device patented to F. Sprower, No. 211,431, of January 14, 1879, in which two metal pieces are formed, each with 85 a flange, adapted to serve together as a ferrule, and the flanges to bear against the handle when turned down.

I am also aware that it is not broadly new to employ a single piece of metal to serve both 90 as an upper plate and inclosing sides; but such is not slotted, not locking with itself, nor locking with the handle. The advantages of my construction in these respects are obvious.

What I claim is—

The brush herein described, having the metal part D D' formed in one piece, slotted at d, and locked by slot d' and tongue d'', in combination with the handle A A', grooved at a, as herein specified.

In testimony whereof I have hereunto set my hand this 12th day of August, 1879, in the presence of two subscribing witnesses.

HUBBARD HENDRICKSON.
